CLAIM

The ornamental design for an autoinjector, as shown and described.

DESCRIPTION

FIG. 1 is a perspective view showing a new design for an autoinjector with a removable cap;

FIG. 2 is a right side view of the autoinjector and removable cap of FIG. 1;

FIG. 3 is a left side view of the autoinjector and removable cap of FIG. 1;

FIG. 4 is a front view of the autoinjector and removable cap of FIG. 1;

FIG. 5 is a rear view of the autoinjector and removable cap of FIG. 1;

FIG. 6 is a top view of the autoinjector and removable cap of FIG. 1 showing the top of the removable cap while positioned on the autoinjector; and,

FIG. 7 is a bottom view of the autoinjector of FIG. 1.

(Continued)

The dashed lines showing portions of the autoinjector are included for the purpose of illustrating environment and form no part of the claimed design.
